REMOVABLE SHOE HEEL AND LIFT

Bern Jassen, Brooklyn, N. Y.

Application May 29, 1933. Serial No. 673,412

17 Claims. (Cl. 36—42)

In U. S. Letters Patent No. 1,888,765, dated November 22, 1932, there is shown a detachable heel lift for shoes and the present invention, among other things, embodies improvements over the article shown in said patent.

One object of the present invention is to provide an article of footwear having a detachable heel which may be readily removed by the wearer and be replaced with another heel, without having to resort to the services of a shoe maker or cobbler. In some instances, especially with the heels commonly worn by women, the heel becomes detached from the shoe, or the heel body, usually made of wood, leather, or some composition material, becomes broken. When either of these occurs with the common type of footwear it is necessary to take the shoe to a shoe maker or cobbler to have the heel repaired or replaced. Where the latter is necessary the cobbler is not likely to have in stock a heel of the right shape, finish and color to replace the broken one; and it is necessary to send the shoe back to the manufacturer or to discard the pair of shoes completely.

Where shoes are supplied with the present invention the user may readily detach a broken heel and replace it with a new one with no more tools than a screw driver or the end of a shoe horn. If desired, the user may be supplied with more than one pair of heels for one pair of shoes, which heels may be of different colors to obtain different color combinations and the user may attach either set of heels to the shoes. Or, multiple sets of heels of relatively different shapes or heights may be supplied for the same pair of shoes so that the user may obtain different combinations of heels and footwear. Or, a dealer may alter the heels of any pair of shoes to obtain different color combinations to suit the tastes of customers without having to carry in stock a multitude of individual styles.

The present invention provides means for readily and easily detaching the heel from the shoe to obtain any of the results referred to, and a new or different heel may be readily applied to replace the one removed. The present device for securing the heel to the shoe is invisible when the heel is applied so that it does not detract from the appearance of the shoe.

In the fullest embodiment of my invention the means for detachably securing the heel to the shoe is combined with the means for detachably securing the lift to the heel so that some of the parts are common to both devices.

The other branch of my invention relates to a simple means for detachably securing the lift

to the heel. Lifts wear down either across the whole bottom surface or at one side or the back, very quickly and if not renewed the shoe may be thrown out of shape. In some cases a lift may wear only a week or two, especially on women's shoes where the wearing area is very small; and it is necessary for the wearer to have a cobbler put on new lifts at these frequent intervals. This is both inconvenient and expensive.

With the present invention the user, without any tools whatever, may, in a matter of seconds, remove the worn lifts and replace them with new ones, and at a cost of only a few cents a pair because the lifts alone may be sold at a price of a few cents a pair. The wearer may find upon dressing for some occasion and at a time when no cobbler is available, that the lifts are worn on the shoes she most desires to wear. If they are equipped with the present invention it is only a matter of seconds to change the lifts.

One object of my present invention so far as it relates to the lift device is, to provide a lateral extension on the lower end of the sleeve which is forced into the bore in the heel body, and to provide means for engaging this lateral extension to prevent the sleeve from turning. This is especially important where the detachable heel feature is employed with the detachable lift feature, because the sleeve is prevented from turning or shifting when the heel securing nut is being tightened. It also prevents the sleeve turning when the lift holding member is turned in relation to the heel. The means for preventing the sleeve from turning in the heel preferably consists of pins driven into the heel and extending through the sleeve extension referred to, these pins also projecting into apertures in the lift to prevent the latter from turning or shifting while in operative position.

Another object is to arrange the means for preventing the plunger which carries the lift from turning when in operative position, at a point near the bottom of the plunger and therefore near the lift.

Another object is to provide more efficient and simple means to hold the lift retaining member separated from the end of the heel while a lift is being removed or applied and to position this means at the lift end of the device.

Another object is to permit the plunger which carries the lift to be turned in either direction when drawn out, and to have the plunger held out regardless of which direction it is turned. The turning of the plunger when it is pulled out and

turned has no tendency to turn the sleeve in the heel bore.

Another object is to provide a lift which may be made of leather and having a plate attached thereto to cooperate in forming the slot and pocket for receiving the lift holding plate. This makes it unnecessary to form the pocket and slot in the lift itself, which is especially economical where the lift is made of leather.

10 Another object of my invention is to simplify and reduce the cost of the parts and to simplify and cheapen the cost of assembly. Other advantages will be set forth in the following detailed description of the invention.

15 In the drawing forming part of this application,

Figure 1 is a plan view of the rear or heel portion of a woman's shoe or oxford, with the inner lining partly lifted to show the nut which is part of the heel securing means,

20 Figure 2 is a longitudinal sectional view taken on the line 2—2 of Figure 1.

Figure 3 is a detail sectional view, taken on the line 3—3 of Figure 2,

25 Figure 4 is an elevational view, the major portion of which is broken away and showing the heel and lift attaching parts on an enlarged scale.

Figure 5 is an assembly view of the device,

Figure 6 is a perspective view of the sleeve,

30 Figure 7 is a perspective view of a stamped form of plunger,

Figure 8 is an inverted view of a modified form of lift,

Figure 9 is a sectional view taken on the line 35 9—9 of Figure 8, and

Figure 10 is a side elevation of the lift shown in Figure 8.

I will first describe the form of the invention shown in Figures 1 to 5. I have shown only the 40 rear portion of heel 1, of a shoe or oxford such as are worn by women, as the remainder of the article may conform to present practice. The inner lining 2 has been lifted up to permit access to the securing nut. The heel 3 which is fitted to the heel seat 4, may be of any shape so far as the present invention is concerned and I have shown it as the high or French type. The body of the heel may be made of wood, leather or any of the composition materials employed for this 45 purpose and it may be covered with leather, celluloid or any of the finishing materials commonly used for such purpose. In other words, the heel may be made according to present practice except that it is provided with a bore 5, which, if all the 50 features of my invention are used, will extend from the bottom end of the heel right through to the top. Preferably, the upper portion 6 of the bore is widened or enlarged and it is inclined at an angle to the lower portion as shown in Figure 55 2, to accommodate the bolt.

There is a sleeve 7 which has a driven fit in the lower portion of the bore 5 of the heel; and at its bottom end the sleeve has lateral wings or flanges 8 which rest against the bottom end of the heel to determine the position of the sleeve in the heel and for another purpose as will appear.

60 The wings or flanges 8 each have an aperture 9 through which pins 10, driven into the body of the heel extend so that these pins prevent the sleeve from turning in the bore 5. They serve an additional function, as will appear. The sleeve 7 is rolled or crimped near the bottom edge as shown at 11 to form an inner projection to provide an abutment for one end of the coiled spring 12. This spring surrounds the plunger 13

which extends into the bore of the sleeve. The other end of the spring abuts against the collar 14 on the upper end of the plunger, the collar being held on the plunger by turning over or swaging the end of the plunger as shown at 15. An indentation 16 may be provided in the end of the plunger to facilitate this swaging operation. The spring has a tendency to force the plunger upwardly within the sleeve.

65 The heel lift shown in Figures 1, 2, 3 and 5 is shown as having a straight or slightly curved front edge 17 to conform with the breast of the heel; and it has rounded side and rear edges 18 to conform with the contour of the lower end of the heel. The lift is of uniform thickness. It is provided with a pocket 19 extending horizontally inwardly from the front edge 17 and there is a slot 20 extending from the front edge 17 which slot extends from the pocket 19 to the top of the lift. There are recesses 21 formed in the top side of the lift, shown at opposite sides of the slot 20 to receive the lower ends of the pins 9a.

70 The lower end of the plunger is provided with a shoulder 22, preferably two of them disposed at opposite sides of the plunger, which are adapted to move into the slots 23 in the ends of the sleeve 7 when registered therewith, but which are adapted to rest with their top edges against the end of the heel to hold the plunger partially withdrawn from the sleeve, as will be described hereinafter.

75 There is another shoulder 24 on the plunger, the purpose of which is to close the front end of the slot 20 of the lift when in operative position, to exclude dirt from the inner parts.

80 On the extreme lower end of the plunger there is a laterally extending plate 25 which is adapted to be received in and preferably fit the pocket 19; and this plate is shown as having the portion 26 which first enters the pocket 19 rounded. This 85 plate has cut outs or recesses 27 to permit the pins 10 to pass therethrough and enter the recesses 21 of the lift. Where the detachable heel feature is employed, the sleeve is extended above the end of the plunger to receive therein the ball 28 which 90 is formed on the lower end of the bolt 29. The end of the sleeve is preferably crimped or spun inwardly as shown at 30 to hold the ball from moving out but permitting it to turn. There is a pin 31 driven through a cross aperture in the 95 ball and the ends of the pin pass through the elongated slots 32 in the sleeve. This pin may rock in one direction due to the play in the slots 32 while the ball may rock with the pin at right angles to the first movement, thereby permitting a 100 universal movement of the ball.

105 There is an aperture 33 formed through the heel seat of the shoe, of sufficient diameter to receive therethrough the cylindrical portion 34 of a nut. This nut has a thin top 35 adapted to rest against the top wall of the heel seat under the inner lining 2; and the cylindrical portion extends through the aperture 33 in the heel seat. It has an internal thread 36 for engagement with the external thread 37 of the bolt 29 whereby the nut 110 may be screwed onto the upper end of the bolt.

115 *Operation.*—In assembling the parts the plunger 13 is inserted into the sleeve 7; then the spring 12 is dropped into the sleeve from the top so that it surrounds the plunger and rests against the crimped shoulder 11 of the sleeve. The collar 14 is then placed on the upper end of the plunger and is pressed down on the spring 12. While the collar is held down, a tool is tapped against the hollowed end of the plunger to turn the edge 120 125 130 135 140 145 150

over above the collar as shown at 15. The sleeve, spring and plunger are now assembled. The ball 28 may be placed in the upper end of the sleeve and then the end of the sleeve is spun in as at 30 5 to confine the ball. Either before or after this is done the pin 31 is driven into the cross aperture of the ball with the ends of the pin extending into or through the apertures 32 of the sleeve.

The device is now ready to be assembled in the 10 shoe. The sleeve 7 is driven into the bore 5 of the heel until the wings 8 rest against the end of the heel. The top of the heel is now placed against the heel seat 4 of the shoe. The cylindrical portion 34 of the nut is passed through 15 the aperture 33 of the heel seat and it is turned until the threads 36, 37 engage and the nut is further turned until the bolt is pulled upwardly and the nut drawn down tightly against the inside of the shoe, whereupon the heel will be tightly clamped in position on the shoe. There are pins or nails 38 in the top of the heel which pierce the heel seat as the heel is drawn into final position and these serve to prevent the heel from turning about the bolt.

20 The top of the nut may be provided with the cross slot 39 to be engaged by a screw driver or the edge of a shoe horn, for the purpose of turning the nut in the manner described.

25 The plate 25 is grasped by the hand and is pulled away from the end of the heel against the resistance of the spring 12 acting on the plunger; and when the shoulders 22 have been moved out of the slots 23 of the sleeve, the plate 25 and plunger 13 may be turned around either 30 clockwise or counterclockwise; and this will bring the top edges of the projections 22 at such positions that they may rest against the end of the heel. If the plate 25 is now released, the plate 35 and the plunger will be held in their downwardly projected position shown in dotted lines in Figure 4. The plate 25 is now spaced from the end of the heel to permit the lift to be attached. The lift is approached to the plate 25 as shown in 40 Figure 5 and it is pushed onto the plate so that the latter enters the pocket 19 and the portion 45 enters the slot 20 until the end of the plate stops against the end of the pocket 19.

The lift and the plate 25 (and of course the plunger) are now turned until the portion registers with the slots 23 in the lower end of the sleeve. Immediately, the plunger is drawn up by 50 the spring 12 until the lift is pressed against the end of the heel by the plate 25. As this action takes place, the pins 9a pass through or into the 55 cut outs 27 of the plate 25 and enter the apertures 21 of the lift. These pins not only prevent the sleeve from turning or shifting in the heel but they also prevent the lift from turning or shifting on the heel. The shoe is now ready for 60 wearing. The projection 24 serves to close the end of the slot 20 and prevent the entry of dirt.

If it is desired to replace the lift the above 65 operations are reversed. The lift is pulled down from the heel and this carries the plate 25 downwardly. When the shoulder 22 is flush with or below the end of the heel the lift, the plate 25 and the plunger are turned until the shoulder 22 lies and rests against the end of the sleeve, whereupon the lift may be released and the plate 25 70 will be held down. The old lift may be slid off the plate 25 and a new lift placed on it and then the lift is turned as before to bring the member again into register with the slots 23.

In Figures 6 and 7 I have shown the detachable 75 lift feature without the removable heel feature.

Herein the sleeve 7 is the same as before except that it need not be as long. The plunger consists of a continuous strip of metal bent back upon itself so that the superimposed portions form the plunger. The two half plates 40 perform the same function as the plate 25 in the first form of the invention. The shoulders 41 and 42 perform the same functions as the shoulders 22 and 24 of the first form. There is a collar 43 placed on the upper end of the plunger for the spring 12 to rest against and this may be held in place by a pin 44 passing through the loop 46 and having its ends 47 bent up to prevent the pin from sliding out of place. The plunger and the plate 40 operate the same as in the first form of the invention.

In Figures 8 to 10 I have shown a modified form of lift. Where the latter is made of leather the pocket 19 and the slot 20 can not be cast therein. Here I attach a plate 48 to the top of the lift, preferably by forming the three lugs 49 on the edge of this plate, which lugs are forced through the lift material and clenched as shown. The space 50 between the plate and the lift forms a pocket corresponding with the pocket 19. The slot 51 in the plate 48 serves the same purpose as the slot 20. This form of lift is applied to and removed from the plate 25 in the same manner as the first lift.

By having the bolt 29 connected with the sleeve 105 through a swivel connection, the heel may fit properly against the heel seat and its position controlled by the latter. The heel attaching device is useful regardless of whether the heel is ever to be removed and replaced, because it provides a stronger and more dependable means for securing the heel to the shoe. The bolt shown herein is stronger and more reliable than the means heretofore used for attaching heels to 110 foot wear. The heel is therefore less likely to 115 be broken or to come off the shoe.

Having described my invention, what I claim is:

1. A lift attachment for an article of footwear including a heel having a bore, a sleeve extending upwardly in said bore, said sleeve having a slot in its lower end, a plunger movable in said sleeve and having a lift carrying plate adjacent the lower end of the heel, a spring in said sleeve for urging said plunger and plate upwardly to clamp 120 a lift carried by said plate against the bottom of the heel, and means carried by said plunger, adapted to be registered with said slot in the sleeve to allow the lift carried by said plate to be pressed against the bottom of the heel.

2. A lift attachment for an article of footwear including a heel having a bore, a sleeve extending upwardly in said bore, said sleeve having a slot in its lower end, a plunger movable in said sleeve and having a lift carrying plate adjacent the lower end of the heel, a spring in said sleeve for urging said plunger and plate upwardly to clamp 125 a lift carried by said plate against the bottom of the heel, and means carried by said plunger, adapted to be registered with said slot in the sleeve to allow the lift carried by said plate to be pressed against the bottom of the heel, said plate being adapted to be turned to allow said means to extend across said slot and serve as an abutment to temporarily hold said plate separated 130 from the bottom end of the heel to receive a lift thereon.

3. A lift attachment for an article of footwear including a heel having a bore, a sleeve extending upwardly in said bore, said sleeve having a 135

- slot in its lower end, a plunger movable in said sleeve and having a lift carrying plate adjacent the lower end of the heel, a spring in said sleeve for urging said plunger and plate upwardly to clamp a lift carried by said plate against the bottom of the heel, and means carried by said plunger, adapted to be registered with said slot in the sleeve to allow the lift carried by said plate to be pressed against the bottom of the heel, said plate being adapted to be turned to allow said means to extend across said slot and serve as an abutment to temporarily hold said plate separated from the bottom end of the heel to receive a lift thereon, said abutment means being so constructed and arranged that when it extends into said slot in the sleeve it will prevent the lift plate from turning in relation to the heel. 80
4. A lift attachment for an article of footwear, including a heel having a bore, a sleeve extending upwardly in said bore and having a slot in its lower end, a plunger movable in said sleeve, a lift carrying plate on said plunger below the heel, an abutment member carried by said plunger, adapted to enter said slot in the sleeve when registered therewith, and adapted when positioned across said slot to temporarily hold the plunger so that said plate is spaced from the bottom of the heel to permit a lift to be placed on or removed from said plate. 85
5. A lift attachment for an article of footwear, including a heel having a bore, a sleeve extending upwardly in said bore, and having a lateral extension on its lower end resting against the bottom of the heel, means extending through said lateral extension and entering the heel to prevent said sleeve from turning in said bore, a plunger movable in said sleeve, spring means for drawing said plunger upwardly, and a plate carried by said plunger for receiving a lift and for pressing it against the bottom of the heel. 90
6. A lift attachment for an article of footwear, including a heel having a bore, a sleeve extending upwardly in said bore, and having a slot in its lower end, said sleeve having a lateral extension at its lower end resting against the bottom of the heel, means extending through said lateral extension and entering the heel to prevent the sleeve from turning in said bore, a plunger movable in said sleeve, spring means for drawing said plunger upwardly, a plate carried by said plunger for receiving a lift thereon and an abutment member carried by said plunger adapted when registered with the slot in said sleeve to allow the plunger to move to a higher position and when placed crosswise of said slot to hold said plunger in a lower position. 100
7. A lift attachment for an article of footwear, including a heel having a bore, a sleeve extending upwardly in said bore, and having a lateral extension at its lower end resting against the lower end of the heel, a plunger movable in said sleeve, spring means for drawing said plunger upwardly, a plate carried by said plunger for receiving a lift and for pressing it against the bottom of the heel, and means extending into the heel and passing through said lateral extension and adapted to project into a lift pressed by said plate against the heel. 105
8. A lift attachment for an article of footwear, including a heel having a bore, a sleeve extending upwardly in said bore and having a lateral extension at its lower end resting against the lower end of the heel, a plunger movable in said sleeve, spring means for drawing said plunger upwardly, a plate carried by said plunger for receiving a lift and for pressing it against the bottom of the heel, and pins extending into the heel and passing through said lateral extension and said plate and into a lift pressed by said plate against the heel. 110
9. A lift attachment for an article of footwear, including a heel having a bore, a sleeve extending upwardly in said bore, and having a lateral extension crimped inwardly to form an abutment near its lower end, a plunger, a spring in said sleeve surrounding said plunger and resting at one end against said abutment, means on said plunger for the upper end of the spring to engage so that the spring pulls the plunger upwardly, and a lift retaining plate on the lower end of the plunger for pressing a lift against the lower end of the heel under the action of said spring. 115
10. A lift attachment for an article of footwear, including a heel having a bore, a sleeve extending upwardly in said bore, said sleeve having an abutment near its lower end, a plunger in said sleeve, a spring in said sleeve surrounding said plunger with one end resting against said abutment, a collar on the upper portion of the plunger, to form an abutment for the upper end of the spring, said plunger being upset to hold said collar, and a lift retaining plate on the lower end of said plunger, for pressing a lift against the lower end of said heel. 120
11. As a new article of manufacture a heel lift including a lift body, a plate having lugs piercing said body to hold the plate thereon to form a pocket between said plate and said body to receive an attaching plate, said first plate having a slot therein to receive a member by which said attaching plate is carried. 125
12. As a new article of manufacture a heel lift including a lift body, a plate having lugs piercing said body to hold the plate thereon to form a pocket between said plate and said body to receive an attaching plate, said first plate having a slot therein to receive a member by which said attaching plate is carried, said first plate also having apertures on opposite sides of said slot to receive pins therein. 130
13. An article of footwear having a heel seat, having an aperture therethrough, a heel having a top to fit said seat, said heel having a bore therein, a sleeve secured in said bore, a bolt pivotally attached to said sleeve, and a nut arranged above said heel seat and adapted to be secured to said bolt through said aperture whereby when said bolt and nut are screwed one upon the other said heel will be drawn tightly against said heel seat said nut being disposed at an angle to said sleeve. 135
14. An article of footwear having a heel seat having an aperture therethrough, a heel having a top to fit said seat, said heel having a bore therein, a bolt secured in said bore, a nut having a cylindrical portion extending through the aperture in said seat and a head resting against the top of the heel seat within the article of footwear said nut being adapted to be revolved when in position on said seat, said cylindrical portion of the nut having a threaded engagement with said bolt, whereby when said bolt and nut are screwed one upon the other by the revolving of the nut said heel will be drawn tightly against said heel seat. 140
15. An article of footwear having a heel seat having an aperture therethrough, a heel having a top to fit said seat, said heel having a bore, anchoring means in said bore, a bolt pivotally 145

connected with said anchoring means and a nut above said heel seat and adapted to be secured to said bolt through said aperture whereby when said bolt and nut are screwed one upon the other 5 said heel will be drawn tightly against said heel seat.

16. An article of footwear having an apertured heel seat, a heel having a top to fit against said seat, said heel having a bore therethrough, 10 a sleeve in said bore and having means engaging against the bottom of the heel, a bolt pivotally connected with the upper portion of the sleeve, a nut in the article of footwear and having a threaded connection with said bolt through the 15 heel seat, a plunger in said sleeve, spring means

for drawing the plunger upwardly in the sleeve, and a plate carried by said plunger and adapted to receive a lift thereon and to press the same against the bottom of the heel.

17. An article of footwear having a heel seat having an aperture therethrough, a heel having a top to fit said seat, said heel having a bore, anchoring means in said bore, a bolt connected with said anchoring means by a universal joint and a nut above said heel seat and adapted to be secured to said bolt through said aperture whereby when said bolt and nut are screwed one upon the other said heel will be drawn tightly against said heel seat. 80 85
